MARTIN R. KENYON, OF PROVIDENCE, RHODE ISLAND.

Letters Patent No. 87,854, dated March 16, 1869.

IMPROVEMENT IN BUTTONS.

The Schedule referred to in these Letters Patent and making part of the same.

To all whom it may concern:

Be it known that I, MARTIN R. KENYON, of the city and county of Providence, in the State of Rhode Island, have invented a new and improved "Button, or Stud;" and I do hereby declare that the following specification, taken in connection with the drawings, making a part of the same, is a full, clear, and exact description thereof.

Figure 1 shows the proper size of my improved stud.

Figure 2 shows the position of the parts previous to inserting the stud in the bosom.

Figure 3 is a view of the same, after insertion in the bosom.

Figure 4 is a bottom view.

Figure 5 is a view of the edge.

Studs and sleeve-buttons have heretofore been the subject of many patents, and many useful improvements have been made in this class of inventions; the object of each and every inventor being to produce something which might easily be adjusted to the garment, without wrinkling or injuring it, and when once adjusted, not liable to become disengaged and lost, yet few of the many inventions have possessed that simplicity of construction, which, in an article so small, is essential to its durability, and fewer still, have been any real improvement upon the old-fashioned button-stud, which is much objected to, as its use almost always results in an injury to the appearance of the garment or article to which it is attached.

In my invention, which I will now proceed to describe, I have endeavored to preserve the durability of the old button-stud, and at the same time produce a stud, which, for ease and facility of adjustment, shall be superior to others now in use.

In the drawings—

A, fig. 2, is the top of the stud, and B, the shank. The shank B is mortised its entire length, for the purpose of receiving two levers, or elbows, C and D, which are attached to the lower end of the shank, by means of a pin or rivet, E.

The stud being ready for use, the parts occupying the position shown in fig. 2, the arms H and H' are inserted in the eyelet-hole, until the points a and a', upon the arms K and K', come in contact with the cloth, when, by the pressure of the thumb or finger upon the top, A, the arms K and K' come together and fill the mortise in the shank B, the arms H and H' at the same time spreading apart upon the other side of the cloth.

The parts now occupy the position shown in fig. 3, and the button is securely fastened to the garment.

Whenever it is desired to remove the stud, the wearer takes hold of the top, A, and pulls it out. The pressure upon the arms H and H' brings them again together, the parts resuming their former position, as shown in fig. 2.

I do not confine my invention to bosom-studs entirely, as the same device may be used in sleeve or other buttons.

What I claim as my invention, and desire to secure by Letters Patent, is—

The combination of the button-head A, shank B, elbows C and D, and arms H and H', the whole constructed and arranged substantially as described, for the purposes specified.

MARTIN R. KENYON.
